REVERSIBLE PUMP WITH AUTOMATIC VALVING

Hiram H. Haight and Wayland Z. Haight,
Wauwatosa, Wis.

Application February 12, 1952, Serial No. 271,206

13 Claims. (Cl. 103—117)

This invention relates to a reversible pump with automatic valving.

It is the objective of the invention to provide an unusually compact design with unusually free flow for the fluids pumped. To this end, a pump body with removable end closures and containing at least one pumping rotor has inlet and discharge passages cored in part in the body and in part in the covers of said closures which project into the body to confine the rotor, the said passages extending partially across at least one face of the rotor.

Two of said passages terminate in a valve chamber which extends transversely of the rotor axis but preferably in the same plane with the rotor, into which chamber project removable cages which provide guide surfaces and seats for a pressure-reciprocated valve movable between said cages across a portion of the valve chamber with which a port communicates.

In the preferred construction, there are three inlet and discharge passages, each of which is branched to extend along opposite faces of the rotor or rotors and opening into the pump chamber at points roughly centered at about 120° of spacing. Moreover, the respective discharge passages controlled by the valve desirably have their branches at opposite sides of the body respectively extended into closer proximity to the dead center position of the rotor than are the alternate branches of the discharge passages, the object being to provide for the escape of fluid at maximum pressure without reducing the sealing area between the openings of the respective passages.

In the drawings:

Fig. 1 is a front elevation of a pump embodying our invention, portions of one of the heads and the pump rotor means being broken away to a transverse section.

Fig. 2 is a side elevation of the pump with portions of one of the heads and the body being broken away to a section parallel to the axial section.

Fig. 3 is a view in transverse section on the plane indicated at 3—3 in Fig. 4.

Fig. 4 is a view in axial section on the plane indicated at 4—4 in Fig. 3.

Fig. 5 is an enlarged fragmentary detail view of the valve structure showing the valve in a position opposite to that in which it appears in Fig. 3.

Fig. 6 is a view taken in section on line 6—6 of Fig. 3.

Fig. 7 is a side elevation of a modified embodiment of the invention.

Fig. 8 is a view in end elevation of the device in Fig. 7, portions being broken away to expose the interior construction.

The body portion 7 of a pump embodying the invention is provided unitarily with a pumping chamber 8 and the valve chamber 9. While the type of pumping mechanism in the pumping chamber is broadly immaterial to the invention, the pumping mechanism preferably comprises a gear pump including at least one rotor driven by shaft 10. The invention is particularly adapted for

2

use in a pump of the type having a ring gear 11, a displacement pinion 12 meshing with the ring gear eccentrically thereto, and a crescent-shaped baffle at 13. In the instant pump, selected to exemplify the invention, the pinion is the rotor connected with drive shaft 10 and the ring gear is idle. The converse arrangement is well known.

The respective closures 15 and 16 have bosses 17, 18 extending into the pump chamber at opposite ends of the rotor or rotors therein to close such chamber. The respective flanges 19 and 20 of the closures 15, 16 seat against the ends of the pump body 7, being held thereto by bolts 21, 22. The bolts 21 alternate with bolts 22 and are shorter, being threaded into tapped openings provided in the flange 19. The longer bolts 22 extend completely through flange 19 to make their threaded ends available for mounting the pump. Suitable bearings and packing are provided for shaft 10 within the respective end closures. End closure 16 may have a removable subclosure at 23 affording access to its bearing 24. The bearing structures, however, form no part of the present invention.

The pump inlet 25, which may have any desired type of pipe connection through the provision of a removable cap 26, communicates with branch inlet passages 27, 28 formed in the pump body 7 and leading to channels 29 and 30, respectively, which are formed in the inner faces of the bosses 17 and 18 of the end closure and which extend across the opposite faces of rotor 11 as best shown in Fig. 4. The channels 29 and 30 have a radial extent inwardly from the outer periphery of rotor 11 across the baffle 13 and into the path of travel of the teeth of the pinion rotor 12 so that liquids or gases admitted through the inlet 25 can reach the interdental spaces of both rotors to relieve vacuums therein resulting from the disengagement of their teeth, following the discharge of fluid from the high pressure side of the pump in the manner presently to be described.

Two separate paths of flow are provided from the high pressure side of the pump and there are two channels for each such path of flow, or a total of four separate channels for discharge. Each of the four channels extends across a face of rotor 11.

Assuming the rotors 11 and 12 to be turning counter-clockwise as viewed in Fig. 3, the fluids admitted to the interdental spaces through channels 29 and 30 will be expelled from such spaces as the teeth of the pinion and ring gear mesh above the horizontal center line through the pump chamber 8. Extending from such center line, at opposite sides of the rotors, are the channels 33 and 34. It will be observed that the entire area of each of these channels is exposed to the interdental spaces for the escape of fluid there from as the teeth approach their positions of maximum mesh. Channel 33, however, extends closer than does channel 34 to the vertical center line and is a counterpart, in this respect, of channel 36 which is shown in dotted lines at the other side of the vertical center line in Figs. 1 and 3.

Channels 33 and 34 merge in passage 37 in the pump body 7 (Fig. 2) which passage opens into the valve chamber 9 subject to the control of a valve hereinafter to be described. Channels 35, 36 merge in passage 38 in the pump body 7, which leads to the opposite end of the valve chamber 9, subject to the control of said valve, as is now to be described.

The valve chamber 9 is a transverse bore extending through the pump body 8 from one side to the other. Replaceable plugs 39 and 40 have their heads bolted to the pump body as best shown in Figs. 2 and 3. The respective plugs 39 and 40 have lateral openings 41, 42, respectively communicating with the body passages 38 and 37. The plugs have generally axial bores 43, 44 intersecting,

and communicating with, the lateral openings 41, 42 respectively.

At their mutually spaced ends 45, 46, the plugs have counter bores 47, 48 which terminate at the valve seat shoulders 49, 50, respectively. Rather closely fitted to the counter bores to be movable across the gap between the plug ends 45 and 46 is a ball valve 51 which may be actuated by pressure differentials to seat either at 49 or 50 to permit one of the body passages 37 or 38 to communicate through the respective lateral openings 41 or 42 and the appropriate bore 43 or 44 of the respective plugs with the space between the ends 45 and 46 of the plugs, which space opens into the valve chamber 9. In registry with this space, the valve chamber 9 intersects the discharge port 55, which may be capped by any desired coupling fitting 56.

When the pinion 12 and ring gear 11 are turning clockwise as viewed in Fig. 3, the increasing mesh of the teeth will displace the contents of the interdental spaces into channels 35 and 36. The fluids will pass from said branch channels into passage 38 and thence into passages 41 and 43 of the plug 39 to force the ball 51 to its seat 50, thereby permitting the fluids to escape from the counter bore 47 into the discharge passage 55 and outwardly through fitting 56.

If the rotation of the respective gears were counter-clockwise, as viewed in Fig. 3, the displaced fluids would pass from the interdental spaces into channels 33 and 34 and thence through passages 37, 42 and 44 to the discharge port 55, the ball valve 51 being displaced to the left to engage its seat 49.

Figs. 7 and 8 show a conventional type of two-gear pump modified so that it will pump oil in the same direction regardless of the direction in which the gears are operated. The housing 70 has flanges 71 and 72. To the flange 71 is bolted the closure plate 200 formed at 201 to provide a bearing (not shown) for the shaft 100.

Within the housing 70, the shaft 100 carries a gear 110 and a meshing idler gear 120.

The flange or head 72 of the casing is formed to provide an inlet passage 260 having a coupling cap 560. The branches 270 and 280 of the inlet passage 250 extend to ports 290 and 300 communicating with the housing at diametrically opposite points on a line passing through the axes of the respective gears.

Outlet ports 340 and 360 open axially from the housing at points at opposite sides of the line of mesh between gear 110 and idler gear 120. From the outlet port 340, a passage 370 leads to valve chamber 431. From port 360, the passage 380 leads to valve chamber 441. These chambers are respectively formed in the interchangeable plugs 391 and 401 between which there is confined a valve 511, the general organization of this valve and its operation being identical with the constructions already described. The gap between the plugs 391 and 401 provides a passage 91 opening to the outlet port 551 and the coupling fitting 561.

The oil admitted through passage 250 will flow through branch passages 270 and 280 to the ports 290 and 300 to enter the spaces between the respective gears. As the gears mesh, according to their direction of rotation, the oil will be squeezed from between their teeth either into port 340 or port 360 and will traverse either passage 370 or 380 to the valve chamber and will thence flow through the outlet 551. In one direction of rotation, the port 340 will receive the displaced oil. In the other direction of rotation, port 360 will receive the displaced oil. However, the valve 511 will move automatically from one of its seats to the other according to the pressure established by the pump to seal the passage leading to the suction side of the gear mesh and to open the passage leading from the pressure side of the point of gear mesh.

Self-adjusting valves have heretofore been proposed but have not gone into general use. It is believed that non-use is at least partially attributable to the hitherto

unperceived fact that in order to operate successfully the size of the bore controlled by the valve should bear some relationship to the capacity of the pump to assure the development in the bore of adequate fluid velocity for moving the valve positively to its alternate seat when the direction of the pump operation is reversed. Since it would be impracticable to make a completely new pump for each substantial change of flow capacity, the present invention contemplates an arrangement whereby a given pump, capable of handling quite a wide range of capacities, may be equipped interchangeably with plugs having bores and valve seats and a valve of widely different sizes according to the normal pump output. Thus, in Fig. 5, the plugs 39 and 40 of Fig. 3 have been replaced with plugs 390 and 400 of identical external dimensions, but having bores 430 and 440, seats 490 and 500 and a ball valve 510, all of which are materially larger in cross section than the corresponding parts in Fig. 3. The aforesaid plugs and ball valve are freely interchangeable with those shown in Fig. 3 and register in the same manner with the ports 37, 38 and 55 of the pump casing. Thus, regardless of the normal pump flow output, within the wide range of which the pump proper is capable, it is possible at moderate expense to provide interchangeable plug and valve members which will maintain a flow past the valve at sufficient velocity and pressure to move the valve sharply from one seat to the other when there is a change in the direction of rotation.

In all embodiments, the annular clearance between the axially spaced surfaces 45 and 46 of the respective valve insert plugs will be sufficiently narrow so that the ball valve will pass readily from one of the valve seat chambers to the other. Because the discharge passage completely surrounds this annular slot, discharge can take place through the slot in all directions and its capacity is large despite the relative narrowness of the slot.

The fact that each ball fits rather closely in its valve seat bore further assists in assuring the sharp movement of the ball from one valve seat to the other when the direction of rotation of the pump gears is effected.

We claim:

1. A pump casing having bores, opposing closures for one of said bores, said bore comprising a pump chamber, opposing closures for the other of said bores, said other bore comprising a valve chamber, pumping mechanism in the pump chamber provided with a driving shaft for which the closures first mentioned provide bearings, dual valve cages carried by the closures for said other bore in axially spaced relation and provided with valve seats, the said cages having axially aligned passages of materially smaller cross section than the bore cross section and leading from the first mentioned bore to said seats, and a valve pressure-operated from one of said seats across the axial spacing between said cages to the other according to the direction of discharge through said passages, the said casing having an annular discharge port intersecting the path of said valve, said port having a radial extent substantially at least equal to the cross section of the bore whereby to provide circumferential discharge from said passages to said port, the said closures providing axial clearance between said seats communicating with said port for the discharge through said port of fluid from one of said seats.

2. A pump casing having a first bore comprising a pump chamber, meshing pump gears in said chamber one of which is provided with a driving shaft, closures for the ends of said bore connected with said casing to enclose said gears, said casing having an inlet passage opening into said bore at a point remote from the point of mesh of said gears and having a plurality of discharge passages at opposite sides of the casing adjacent the point of mesh of the gears, the said closures extending into the bore and provided with channels extending across the faces of the gears in registry with, and constituting extensions of, said discharge passages, said casing having a second bore intersecting said discharge passages and providing a valve

chamber, and an outlet port intersecting said valve chamber intermediate said discharge passages, and opposing plugs removably positioned in the last mentioned bore and having lateral and axial passages communicating with the discharge passages of the casing and leading therefrom axially of the valve chamber toward said outlet port, and a free moving pressure-operable ball valve controlling flow through the passages last mentioned, the said plugs having ends spaced in the outlet port a distance less than the diameter of the ball and being provided with pockets at opposite sides of said space in which said valve is reciprocably confined, the said plugs further having seats selectively engaged by said valve when the valve is in a respective pocket, the valve being bodily movable across said space from one pocket to the other in response to pressure differential created between said discharge passages according to the direction of rotation of said gears.

3. The device of claim 2 in which each of the said discharge passages is bifurcated, including branches extending from opposite sides of said gears, the said closures having channels leading across the gear sides to each branch, one channel leading to one of said branch passages from one side of said gears originating in immediate proximity to the point of mesh of said gears, and another channel leading to a branch of the other passage at the opposite side of the gears originating in immediate proximity to the point of mesh of said gears, the alternate channels on the respective sides of the gears originating at points relatively more remote from the point of mesh.

4. A pump comprising a casing having a bore opening through the casing and comprising a gear chamber, a pump comprising pinion and ring gear rotors eccentrically disposed and meshing in the gear chamber, one of said rotors having a driving shaft, baffle means interposed between the pinion and ring gear rotors at a point remote from their point of mesh, closures for said gear chamber marginally connected with the casing and having portions extending into said bore in abutment with said rotors and providing support for said baffle means, one of said closures having a bearing for such shaft, the plug portions of the respective closure means providing inlet channels at opposite sides of the rotors for which said casing is provided with a registering inlet passage, the said plug portions of said closures further providing four discharge channels, two of which, at opposite sides of said rotors, lead in opposite directions from points immediately proximate to the point of mesh of said rotors, the other two channels leading in opposite directions from points relatively remote from the point of mesh of the respective rotors, the said casing having discharge passages and branch passages leading from opposite sides of said rotors, one branch of each discharge passage communicating with one of said first mentioned channels and one of the latter channels, the casing being further provided with a bore constituting a valve chamber and with which said transverse passages communicate, plugs fitted in the ends of the valve chamber and connected with said casing and provided with laterally opening passages registering with the discharge passages of the casing aforesaid, said plugs having axial bores into which their laterally opening passages communicate, the said bores leading centrally and the said plugs being counterbored to provide valve pockets and valve seat shoulders to which the said bores open, the ends of said plugs being spaced within the valve chamber, a ball valve confined within said pockets to move across said space between said seats according to the pressure differential developed in the respective discharge passages according to the direction of rotation of said rotors, the said casing having a delivery port intersected by the valve chamber bore and to which the annular space between said plugs opens for the delivery of fluid from the exposed valve seat.

5. In a pump of the character described, a casing provided with at least three laterally spaced passages and a bore intersecting all three passages, two of said

passages being laterally spaced and extending in one direction to said bore, and one of said passages being intermediate said two passages and extending in said direction from the opposite side of said bore, elongated closure plugs connected with said casing and disposed in said bore to close the ends thereof, the respective plugs having their ends spaced from each other within the said intermediate passage, the respective plugs being provided with lateral openings communicating respectively with said laterally spaced passages and further provided with bores extending longitudinally of said plugs from their respective openings to their said respective ends, said plugs being provided with counter bores adjacent such ends to provide valve seats and valve receiving pockets larger than said bore, and a single valve confined by said plugs within their respective pockets for pressure-controlled movement from one of said seats to the other across the intervening space between the ends of said plugs to leave the intermediate passage of said casing in communication with one or the other of said two laterally spaced passages through the opening and bore of a respective plug.

6. The device of claim 5 in which said valve comprises a ball.

7. The device of claim 5 in which said pump casing comprises a pump chamber with which the respective passages leading in the same direction to said bore both communicate, the pump comprising a rotor in said pump chamber, and the respective passages opening from said pump chamber at points angularly spaced respecting said rotor.

8. A pump casing having bores, opposing closures for one of said bores, said bore comprising a pump chamber, separate opposing closures for the other of said bores, said other bore comprising a valve chamber, meshing pump gears in the pump chamber provided with a driving shaft for which the closures first mentioned provide bearings, separate valve cages carried by the closures for said other bore and provided with valve seats, the said closures and casing having registering passages leading from the first mentioned bore to said seats, and a valve pressure-operated along said passages from one of said seats to the other according to the direction of discharge through said passages, the said casing having an annular discharge port intersecting the path of said valve, the ends of said closure cages being spaced to provide clearance between said seats communicating circumferentially with said port for the radial discharge through said port of fluid from one of said seats.

9. The device of claim 8 in which the meshing gears comprise a ring gear and a pinion, said casing having a crescent baffle between the pinion and the ring gear at the side of the pinion opposite from the point of mesh of the pinion with the ring gear.

10. The device of claim 8 in which said gears comprise gears having outwardly projecting peripheral teeth, said casing providing an inlet passage and branch passages leading therefrom to points on the peripheries of the respective gears remote from their point of mesh, said casing further providing branch delivery passages leading to the respective registering passages from points in close proximity to, and at opposite sides of, the point of mesh of said gears.

11. A valving device for a reversible pump having a pump chamber and an inlet and dual outlet ports, said valving device comprising a valve chamber having a central outlet and aligned sockets, separate closures for said sockets, separate tubular valve cage means in the respective sockets and having inner end portions spaced in said chamber, the ends of the cage means having counterbores providing valve seats, a valve reciprocable in the aligned counterbores of said cage means across the space between said end portions and engageable with the respective seats, and passage means providing connections to the tubular cage means from the respective

outlets of said pump, said cage means being interchangeable with like cage means of different size counterbore, valve and passage means whereby to accommodate said valving device to varying rates of pump output.

12. A valving device for a reversible pump with a dual outlet, said valving device comprising a valve chamber having a central outlet and aligned bores, closures for the respective bores, valve cage means carried by the closures and provided with valve seats and counterbored housings about said seats, the said cage means and valve chamber having complementary passages leading from the respective pump outlets to the respective cages, and a ball valve pressure-operated from one of said seats to the other according to the direction of discharge through said passages, the said cages being provided with end walls spaced apart less than the diameter of the ball valve whereby the ball valve is guided to and from said seats in said counterbored housing while providing clearance between said seats communicating with the valve chamber outlet for the discharge through said outlet of fluid from one of said seats when the valve is engaged with the other.

13. A valving device comprising a casing having two inlet passages and a central outlet passage between said inlet passages, a bore intersecting all of said passages, closures detachably connected with the casing at the ends of said bore, each of said closures including a valve cage spanning one of said inlet passages and extending into the outlet passage, the respective valve cages having aligned bores and counterbores and having their inner ends spaced to afford communication between the counterbores and said chamber at an intermediate point open-

ing into the outlet passage, together with a valve reciprocable in the counterbores of the respective cages across the space between said cages, the respective cages having valve seats respectively engageable by said valve according to pressure differentials between said inlet passages, said valve exposing the counterbore of one cage for discharge to said outlet passage when the valve is engaged with the seat of the other cage, whereby to accommodate flow from one of said inlet passages to the outlet passage of said casing according to the position of said valve, said closures being interchangeable with like closures of different size bores, counterbores, and valve whereby to accommodate said valving device to varying rates of flow therethrough.
